Primary Examiner—M. H. Tung*Attorney, Agent, or Firm*—Nikaido, Marmelstein, Murray & Oram**[57] CLAIM**

The ornamental design for an information bearing card, as shown and described.

DESCRIPTION

FIG. 1 is a front view showing my new design;
FIG. 2 is a rear view thereof;
FIG. 3 is a top view thereof, the bottom view being identical;
FIG. 4 is a left side view thereof, the right side view being identical;
FIG. 5 is a front view of a second embodiment, the rear, top, bottom, left side and right side views being identical to FIGS. 2-4 respectively; and,
FIG. 6 is a front view thereof on a reduced scale, the broken line drawing of a card reader being for illustrative purposes only and forms no part of the claimed design.
